GAS HEATER SAFETY DEVICE

Louis F. Durrell, San Antonio, Tex.

Application October 3, 1947, Serial No. 778,146

14 Claims. (Cl. 161—9)

1

This invention relates to improvements in safety devices, and more particularly to an automatic cut-off for gas or other fuel fluids which is operable responsive to change in fluid pressure or change in temperature or operable at termination of a predetermined time period.

It is an object of this invention to provide an automatic cut-off device which may be conveniently interposed in a gas or fuel line leading to a gas or fluid fuel stove, the device including an automatic valve which is actuated by instrumentalities that are operable by the completion of an electrical circuit through the medium of a thermostat or a pressure change actuated device or a conventional electrical timer.

A specific object of this invention is to provide an automatic cut-off device which includes a mechanically-actuated valve that is operably interposed in a gas line leading to any type of gas stove, means opposing the mechanical valve-actuating means and operable to release the valve for automatic operation to cut off the gas for the stove, the valve-releasing means being operated by instrumentalities which are operable by the completion of an electrical circuit through the medium of a bi-metallic temperature-responsive device located adjacent the stove, or a pressure change actuated device operably connected with the gas line leading to the stove, or by a conventional electrical timer.

It is also an object of this invention to provide a gas heater safety device of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportion and minor details of construction may be made within the scope of the claims without departing from the spirit or sacrificing any advantages of the invention.

For a complete disclosure of the invention, a detailed description thereof will now be given in connection with the accompanying drawings, forming part of the specification, wherein:

Figure 1 is a front elevation depicting the improved safety device applied to a gas stove;

Figure 2 is a plan view thereof;

Figure 3 is a perspective view of the thermostat;

2

Figure 4 is a composite diagrammatic perspective view of the electrical circuit and operable components of the improved safety device;

Figure 5 is a schematic wiring diagram showing the electric circuits, switches, and other electrical elements in their normal working positions;

Figure 6 is a schematic wiring diagram disclosing the electric circuits established upon actuation of the mercury switch by virtue of gas pressure failure;

Figure 7 is a schematic wiring diagram showing the electric circuits established upon actuation of the thermostatically controlled switch;

Figure 8 schematically illustrates the electric circuits established upon actuation of the electric timer switch.

Referring to the drawings, in which similar reference characters designate corresponding parts, 10 indicates a casing for housing certain components of the safety device. This casing supports a pipe or conduit 11 having a control valve 12 connected therewith and secured thereto. A nipple 13 extends outwardly from the valve 12 and this nipple is received within a terminal of a flexible conduit or hose 15 which has its opposed terminal connected with the conventional outlet valve or cock 16 of the usual gas supply line or pipe 17, the valve 16 being controlled by manipulating a conventional operating handle 18. The other terminal of the conduit 11 is provided with a nipple 20 which is received within one end of a flexible pipe or hose 21, and the opposed terminal of the hose 21 connects with 35 the gas cock or valve 22 of a conventional gas stove or burner 23. In the present instance, a conventional gas heating stove is depicted which is provided with front guard rails 25, but it is to be understood that the safety device may be employed with any type gas stove or burner.

The usual rotary plug 26 of the valve 12 has a valve stem 27 extending therefrom. The valve stem is provided with a radially-extending detent arm 28 and a terminal reset handle or lever 45 30. A spiral torsion spring 31 has one terminal secured to the stem 27 and its opposed terminal anchored within the casing 10. The torsion spring 31 normally biases the stem for counter-clockwise rotation, for a purpose which will be hereinafter stated.

The outer terminal of the detent arm 28 is adapted to engage a shoulder 32 formed adjacent one terminal of a detent lever 33 which is pivotally mounted intermediate its terminals on a 55 pivot or fulcrum pin 35. A spiral torsion spring

36 is operably interposed between the pin 35 and detent lever 33 to normally bias the lever for pivotal movement in clockwise direction, toward the detent lever 33, about its fulcrum 35, for a purpose to be hereinafter explained. The detent lever 33 is provided at its inner terminal with a downwardly extending manipulating finger 37 and an upwardly extending flange 38. A conventional solenoid 40 is positioned adjacent the flange 38 of the detent lever 33, and this solenoid is provided with an armature stem 41 which is adapted to engage the flange 38, for a purpose to be hereinafter set forth.

A conventional micro-switch 42, normally closed, has its operable projection or stem 43 located in the path of movement of the detent arm 28, and this switch is electrically connected with a conductor 45 which leads to one side of a conventional toggle switch 46. A conductor 47 leads from the opposite side of the micro-switch 42 to one side of the coil of the solenoid 40, and another conductor 48 leads from the opposite side of the coil or solenoid 40 to one terminal 50 of a conventional transformer 51. The transformer 51 is provided with the usual electric cord 52 adapted to be electrically connected with a conventional wall receptacle, not shown.

A Sylphon bellows 53 is connected with the pipe or conduit 11 and is responsive to gas pressure therein, and the outer terminal of the bellows 53 has a pin 55 extending upwardly therefrom. A switch lever 56 is pivotally mounted on a suitably supported axle 57 above the pin 55. The switch lever 56 has a counter-weight 58 secured to its outer terminal and a conventional tiltable mercury switch 60, normally open, is secured to its inner terminal.

A standard electrical buzzer, indicated generally at 61, is supported within the casing 10, and one side of this buzzer is electrically connected with a conductor 62, and the conductor 62 is electrically connected with one side of the toggle switch 46, which is normally closed. A conductor 63 is electrically connected with the opposite side of the electric buzzer 61 and also with the transformer 51 and conductor 48. A conductor 65 is electrically connected with the opposite side of the transformer 51 and to a binding post 66. A conductor 65a electrically connects the binding post 66 with one side of the mercury switch 60. The opposite side of the mercury switch is electrically connected with a binding post 67 through a conductor 45a.

A standard electrical timer 68 is secured within the top portion of the casing 10, and this timer is electrically connected with the binding posts 66 and 67 through electrical conductors 70 and 71. The timer 68 is provided with the conventional setting handle 72 which may be manipulated in conformity with the usual practice to set the timer for actuation at the expiration of a predetermined period of time.

The conventional timer 68 is provided with the usual manually operated switch 95 (see Figures 5 to 9, inclusive) and switches 94 and 97 which are actuated by timer motor 96 at the expiration of the predetermined period.

Under non-automatic control conditions, manual switch 95 is maintained in its open, or "off" position, and switches 94 and 97 have been moved by motor 96 to their open positions, as shown in Figures 5 to 7, inclusive.

When it is desired to use the safety device under automatic conditions, handle 72 is turned to the desired time, closing switch 94 and opening switch 97 (see Figure 8). Manual switch 95 is

then actuated to energize motor 96 which, on the lapse of the desired time period, closes switch 97 and opens switch 94.

The several circuits controlled by switches 95, 94, and 97 are described in detail below.

A thermostat casing 73 is preferably detachably suspended from a front rail 25 of the gas stove 23 by a suspending member or hook 75 extending upwardly from the top of the casing 73. The casing 73 is also provided with laterally extending flanges 76 adapted to engage the uprights or cross bars 25a of the front guard of the stove. By this arrangement, the casing is firmly secured to the front guard of the stove so that the components of the casing are exposed to the temperatures produced by the usual burners of the stove.

A bi-metallic or thermostatic element 77 has its outer terminal 78 anchored within the casing 73. This bi-metallic element is preferably of spiral configuration and has a trip arm 80 secured to its inner terminal, and this arm extends radially with relation to the convolutions of the spiral bi-metallic element. A rock lever 81 has pivotally-supported pintles 82 extending therefrom, and one of the pintles 82 is secured to a spiral torsion spring 83 which functions to normally bias the lower terminal of the rock lever 81 into engagement with the outer terminal of the trip arm 80. The operating terminal or stem 85 of a conventional normally open micro-switch 86 is located adjacent the upper terminal of the rock lever 81, and this micro-switch is electrically connected by conductors 87 and 88, terminating in plug 90 which is detachably connected with socket 92 which is, in turn, connected with binding posts 66 and 67.

Having described in detail the component equipment of this safety device, the operation is deemed manifest, and in this connection, reference is made specifically to Figure 5.

The operator first connects one end of conduit 15 with the gas supply line 17, and the other end thereof is then coupled with nipple 13. Flexible pipe 21 is then connected at one of its ends with nipple 20, while the other end is secured to valve 22. Valve 16 is actuated to admit gas to conduit 15, after which handle 30 is rotated clockwise to the position shown in Figure 4 and becomes interlocked behind shoulder 32 of detent lever 33.

Gas under pressure enters line 11 and actuates pin 55 (due to expansion of bellows 53) to rotate arm 56 in such a manner as to open mercury switch 60 (see Figure 5). Gas burner valve 22 is then opened to admit gas to burner 23. The combustible gas is ignited by any suitable well known means.

Casing 73 containing the thermostatically controlled switch 86 is thereafter mounted on the stove by means of the hook element 75, and is placed in close adjacency to burner 23. When the thermostatic element 77 has been heated sufficiently, arm 80 will rotate counter-clockwise (Figure 3) direction to rotate rock lever 81 in a clockwise direction against the influence of torsion spring 83. In so moving, stem 85 of micro-switch 86 is moved inwardly to open its contacts, as shown in Figure 5. Plug 90, connected with lines 87, 88 is then connected with its complementary socket 92 on casing 10. Socket 90 is connected with binding posts 66, 67, as shown in Figure 4.

The electric timer manual switch 95 is checked 75 to make certain it is in its open or "off" position,

and thereafter, cable 52 is connected with the power supply to energize transformer 51.

Toggle switch 46 is checked to make certain it is closed. With this last operation, the safety device is as shown in Figure 4, and the electric circuits are as shown in Figure 5.

Now let it be assumed that gas pressure in conduit 11 falls below normal. Immediately, bellows 53 contracts to lower pin 55, tilting lever arm 56 to close mercury switch 60. This establishes an electric circuit from transformer 51 through line 65, binding post 66, wire 65a, across mercury switch 60, line 45a, binding post 67, wire 45, across the normally closed micro-switch 42, wire 47, through solenoid 40, and wire 48 to the other side of the secondary of transformer 51.

In completing this circuit, solenoid 40 has been energized, thereby actuating armature stem 41, whereby it engages against flange 38 to pivot detent lever arm 33 on pin 35 against the tension of torsion spring 36. In so moving, detent lever arm 33 moves shoulder 32 away from detent arm 28 to permit it to rotate counter-clockwise with shaft 27 under the influence of spring 31, thereby effecting a closure of valve 12 and cutting off the supply of gas to burner 23.

Detent arm 28, rotating on shaft 27, engages against projection 43 of micro-switch 42, opening its contacts and breaking the circuit through solenoid 40, preventing the solenoid from burning out.

Upon deenergization of solenoid 40, armature stem 41 retracts to permit detent lever arm 33 to rotate to its normal position under the influence of spring 36.

From Figure 5, it is also evident that a second circuit is established when mercury switch 60 is closed. The circuit may be traced from transformer 51, wire 65, binding post 66, across mercury switch 60, wire 45a, binding post 67, wire 45, across the normally closed toggle switch 46, wire 62, through the component elements of buzzer 61, wire 63, and back to transformer 51. Buzzer 61 having thus been energized, continues to sound an audible alarm until toggle switch 46 is opened by the operator.

The position of the switches is now as is shown in Figure 6.

It is now manifest that even if normal gas pressure should be restored in conduit 15, no gas will flow to the burner 23 until handle 30 has been rotated, clock-wise, to the position shown in Figure 4, thereby preventing accidents attendant on the discharge of unignited gas.

In the event normal gas pressure has not been achieved at the time the operator becomes aware of the alarm, any attempt to reignite low pressure gas at the burner 23 by rotating handle 30 to the position shown in Figure 4 will meet with failure as, mercury switch 60 remains closed to energize the aforementioned solenoid circuit whereby shoulder 32 is moved from its locking engagement with detent lever arm 33 to permit its escape and subsequent rotation with shaft 27 to close valve 12.

Assuming that normal pressure has been restored and the buzzer is still sounding an alarm, toggle switch 46 is opened to break the buzzer circuit, handle 30 is rotated clockwise to the position shown in Figure 4, detent lever arm 28 being passed and locked behind shoulder 32. Pressure in conduit 11 again being normal, operates bellows 53 and stem 55 to rock mercury switch 60 to its open position. Toggle switch 46 is then closed and the electric circuits are, again, as shown in Figure 5.

Figure 7 shows the condition of the electric circuits in the event the flame at the burner is extinguished accidentally for reasons other than gas pressure failure. In this event, element 77 cools and rotates arm 80 counter-clockwise to permit rock lever 81 (under tension of spring 83) to rotate against stem 85 closing micro-switch 86.

A circuit is then established from transformer 51 (see Figure 7), wire 65, binding post 66, wire 87, across micro-switch 86, wire 88, binding post 67, wire 45, across switch 42, wire 47, through solenoid 40, and wire 48, to the other side of transformer 51.

Again the solenoid has been energized to expel armature stem 41 which engages shoulder 38 of detent lever 33, to release detent lever arm 28 from behind shoulder 32. Shaft 27 is now free to rotate, closing valve 12 and carrying detent lever arm into engagement with stem 43 of micro-switch 42, breaking the circuit therethrough.

The buzzer alarm circuit is also instantly established leading from transformer 51, wire 65, binding post 66, wire 87, across micro-switch 86, wire 88, binding post 67, wire 45, across toggle switch 46, wire 62, through the elements of buzzer 61, and wire 63, to the other side of transformer 51.

The operator, upon becoming aware of the alarm, opens toggle switch 46, breaking the circuit to buzzer 61. Cause for the extinguishment of the burner flame is then ascertained and corrected. Plug 90 is removed from socket 92, handle 30 is again depressed to the position shown in Figure 4, gas is reignited at burner 23, and toggle switch 46 is closed. After the thermostatic element has been heated to the proper temperature, as described above, plug 90 is reinserted in socket 92. The circuits and apparatus are thus reestablished to the conditions shown in Figures 4 and 5.

It is pointed out that in the event sufficient time lapses between the failure of gas pressure and the discovery thereof to permit thermostatic element 77 to cool whereby switch 86 is closed, it is necessary to disconnect lug 90 from its associated socket 92 and preheat the element before reinserting plug 90 in its complementary socket 92, as just described.

Throughout the foregoing discussion, it has become evident that it is unnecessary for the electric timer 68 to have been rendered operative in order that the positively operating temperature and pressure safety devices should become effective. As an additional feature of this invention, however, the electric timer is provided for convenience, but subject to control by the aforementioned safety pressure and temperature responsive devices.

The timer is conventional in construction, comprising a manually operated switch 95 connected in series with the motor driven switches 94 and 97. The last named switches are operable under the control of timer setting handle 72.

In utilizing this feature of the invention, timer handle 72 is set to the desired time, opening switch 97 and closing motor switch 94 (see Figure 8). Manually operated switch 95 is then closed to start timer motor 96, the circuit reading from transformer 51, wire 65, binding post 66, wire 71, across manual switch 95, wire 71a, wire 98, across switch 94, wire 100, through motor 96, wire 104, and wire 63, back to the other side of transformer 51.

At the expiration of the predetermined time interval, motor 96 drives and opens the motor switch

94, thereby deenergizing the former, and simultaneously therewith closing switch 97. Closing of switch 97 establishes a new circuit reading from transformer 51, wire 65, binding post 66, wire 71, across switch 95, wire 71a, across switch 97, wire 70, binding post 67, wire 45, across micro-switch 42, wire 47, through solenoid 40, and wire 48, to the other side of the transformer 51.

The solenoid, being energized, acts as before to expel armature stem 41 to engage against shoulder 38, rotating detent lever 33 to release detent lever arm 28 from behind shoulder 32, whereby shaft 27 rotates to close valve 12 and to cause engagement of detent lever arm 28 against stem 43 of micro-switch 42. This breaks the circuit to the solenoid, as described above, to prevent its burning out.

It should now be clear that expiration of the predetermined time interval will cause switch 94 of the electric timer to be opened, and switch 97 to be closed as set forth hereinabove. The buzzer 61 will then be sounded by a completed circuit through wire 65, binding post 66, wire 71, across switch 95, wire 71a, across switch 97, wire 70, binding post 67, wire 45, across switch 46, through buzzer 61, and wire 63, back to the other side of transformer 51. The buzzer may be silenced by opening either of manual switches 95 or 46.

To summarize the operation of the safety device described above, the supply of gas to a stove incorporating said safety device may be cut off upon a deficiency of gas pressure, upon the expiration of a time interval as determined by the electric timer, or upon cooling of a bi-metallic switch element due to inadvertent extinguishing of the flame inside the furnace or stove.

In addition to the above gas cut-off safeties, a buzzer is sounded whenever any of the emergencies cited may arise.

It is readily apparent, therefore, that a safety device has been invented which not only prevents a source of danger in the form of free gas, but also serves notice to the operator that a situation has arisen which requires immediate attention if the stove is to be restored to normal heating condition.

Having described my invention in detail, it is to be understood that the invention is not to be limited to the modifications described and illustrated herein, but only by the scope of the appended claims.

Having thus described my invention as new and useful, what I claim is:

1. A safety device in combination with a gas line and a gas burner to which gas under pressure is supplied through the gas line, a valve operably located in the gas line, means for normally biasing the valve towards closed position, a yieldable detent adapted to engage and hold the valve in open position, an electric circuit including a solenoid adapted to operably engage the detent, an electric switch electrically connected to a source of electric current supply and to the solenoid, pressure-responsive means communicated with the gas line and operable to close the switch when pressure drops in the gas line, thereby establishing an electric circuit to the solenoid whereby the solenoid actuates the detent to release the valve for closing to cut off the gas supply to the burner, and timer mechanism electrically connected with the circuit including said solenoid to independently operate the switch upon lapse of a predetermined time.

2. A safety device in combination with a gas line and a gas burner to which gas under pressure is supplied through the gas line, a valve

operably located in the gas line, means for normally biasing the valve towards closed position, a yieldable detent adapted to engage and hold the valve in open position, an electric circuit including a solenoid adapted to operably engage the detent, an electric switch electrically connected to a source of electric current supply and to the solenoid, pressure-responsive means communicated with the gas line and operable to close the switch when pressure drops in the gas line, thereby establishing an electric circuit to the solenoid whereby the solenoid actuates the detent to release the valve for closing to cut off the gas supply to the burner, a thermostat located adjacent the gas burner and operable to establish independently an electric circuit to the solenoid when the temperature drops thereby releasing the valve for closing to cut off the gas supply independent of the gas pressure in the line, and a timer mechanism connected in said circuit including said solenoid and independently operating said switch upon lapse of a predetermined time.

3. A safety device in combination with a gas line and a gas burner to which gas under pressure is supplied through a gas line, a valve operably located in the gas line, means for normally biasing the valve towards closed position, a yieldable detent adapted to engage and hold the valve in open position, a solenoid adapted to operably engage the detent, an electric switch electrically connected to a source of electric current supply and to the solenoid, pressure-responsive means communicated with the gas line and operable to close the switch when pressure drops in the gas line, thereby establishing an electric circuit to the solenoid whereby the solenoid actuates the detent to release the valve for closing to cut off the gas supply to the burner, a thermostat located adjacent the gas burner and operable to establish an electric circuit to the solenoid when the temperature drops thereby releasing the valve for closing to cut off the gas supply independent of the gas pressure in the line, and an electric timer operable to establish an electric circuit to the solenoid at the expiration of a predetermined period of time thereby releasing the valve for closing to cut off the gas supply independently of the gas pressure in the line or temperature at the thermostat.

4. A safety device in combination with a gas line and a gas burner to which gas under pressure is supplied through a gas line, a valve operably located in the gas line, means for normally biasing the valve towards closed position, a yieldable detent adapted to engage and hold the valve in open position, a solenoid adapted to operably engage the detent, an electric switch electrically connected to a source of electric current supply and to the solenoid, pressure-responsive means communicated with the gas line and operable to close the switch when pressure drops in the gas line, thereby establishing an electric circuit to the solenoid whereby the solenoid actuates the detent to release the valve for closing to cut off the gas supply to the burner, and an electric timer operable to establish an electric circuit to the solenoid at the expiration of a predetermined period of time thereby releasing the valve for closing to cut off the gas supply independently of the gas pressure in the line.

5. A safety device in combination with a gas line and a gas burner to which gas under pressure is supplied through a gas line, a valve operably located in the gas line, means for normally biasing the valve towards closed position,

a detent arm movable with the valve, a yieldable detent lever adapted to engage the detent arm to hold the valve in open position, a solenoid adapted to operably engage the detent lever, a tilttable mercury switch normally biased towards open position and electrically connected to a source of electric current supply and to the solenoid, a normally closed bellows communicated with the gas line and operable when open responsive to gas pressure in the line to engage and hold the mercury switch in open position and also operable to disengage the mercury switch to permit it to tilt to closed position when pressure drops in the gas line thereby establishing an electric circuit to the solenoid whereby the solenoid actuates the detent lever to liberate the valve for closing to cut off the gas supply to the burner; and a normally closed switch interposed in the electrical connection between the mercury switch and the solenoid and operably positioned in the path of movement of the detent arm whereby the arm engages and opens the switch after the valve has moved to closed position thereby breaking the electric circuit to the solenoid after the gas has been cut off.

6. A safety device in combination with a gas line and a gas burner to which gas under pressure is supplied through a gas line, a valve operably located in the gas line, means for normally biasing the valve towards closed position, a detent arm movable with the valve, a yieldable detent lever adapted to engage the detent arm to hold the valve in open position, a solenoid adapted to operably engage the detent lever, a tilttable mercury switch normally biased towards open position and electrically connected to a source of electric current supply and to the solenoid, a normally closed bellows communicated with the gas line and operable when open responsive to gas pressure in the line to engage and hold the mercury switch in open position and also operable to disengage the mercury switch to permit it to tilt to closed position when pressure drops in the gas line thereby establishing an electric circuit to the solenoid whereby the solenoid actuates the detent lever to liberate the valve for closing to cut off the gas supply to the burner, and a normally closed switch interposed in the electrical connection between the mercury switch and the solenoid and operably positioned in the path of movement of the detent arm whereby the arm engages and opens the switch after the valve has moved to closed position thereby breaking the electric circuit to the solenoid after the gas has been cut off, and an electric buzzer electrically connected in parallel with the solenoid to audibly indicate when the solenoid is actuated that the gas has been cut off.

7. A safety device in combination with a gas line and a gas burner to which gas under pressure is supplied through a gas line, a valve operably located in the gas line, means for normally biasing the valve towards closed position, a detent arm movable with the valve, a yieldable detent lever adapted to engage the detent arm to hold the valve in open position, a solenoid adapted to operably engage the detent lever, a tilttable mercury switch normally biased towards open position and electrically connected to a source of electric current supply and to the solenoid, a normally closed bellows communicated with the gas line and operable when open responsive to gas pressure in the line to engage and hold the mercury switch in open position and also operable to disengage the mercury switch to permit it to tilt to closed position when pressure drops in the

gas line thereby establishing an electric circuit to the solenoid whereby the solenoid actuates the detent lever to liberate the valve for closing to cut off the gas supply to the burner, a normally closed switch interposed in the electrical connection between the mercury switch and the solenoid and operably positioned in the path of movement of the detent arm whereby the arm engages and opens the switch after the valve has moved to closed position thereby breaking the electric circuit to the solenoid after the gas has been cut off, an electric buzzer electrically connected in parallel with the solenoid to audibly indicate when the solenoid is actuated that the gas has been cut off, and an electric switch interposed in the electrical connection to the buzzer whereby the buzzer may be manually silenced.

8. A safety device in combination with a gas line and a gas burner to which gas under pressure is supplied through a gas line, a valve operably located in the gas line, means for normally biasing the valve towards closed position, a yieldable detent adapted to engage and hold the valve in open position, a solenoid adapted to operably engage the detent, a thermostat located adjacent the burner and including a bi-metallic element operable responsive to temperature variation, a normally open switch electrically connected with the solenoid, a trip arm carried by the bi-metallic element and operable to close the switch when the temperature of the burner drops thereby establishing an electric circuit to the solenoid whereby the solenoid actuates the detent to release the valve for closing to cut off the gas supply to the burner.

9. A safety device in combination with a gas line and a gas burner to which gas under pressure is supplied through a gas line, a valve operably located in the gas line, means for normally biasing the valve towards closed position, a yieldable detent adapted to engage and hold the valve in open position, a solenoid adapted to operably engage the detent, a thermostat located adjacent the burner and including a bi-metallic element operable in response to temperature variation, a normally closed switch electrically connected with the solenoid, a trip arm carried by the metallic element and operable to close a second switch when the temperature of the burner drops thereby establishing an electric circuit to the solenoid whereby the solenoid actuates the detent to close the valve to cut off the gas supply to the burner, said actuation of said detent subsequently operating said first switch to deenergize said solenoid, and a buzzer in said circuit connects in parallel with said second switch and adapted to be operated by said temperature responsive element in response to cooling thereof.

10. A portable safety device in combination with a gas line and a gas burner to which gas under pressure is supplied through a gas line, an electric circuit including a transformer, in combination with a gas line and a normally open mercury switch normally open and operably connected to a pressure responsive device, a solenoid operable to actuate a detent, a valve interposed in said gas line and means normally biasing said valve toward closed position, a switch normally closed interposed between said mercury switch and said solenoid and adapted to be opened upon closing of said valve through actuation of said detent by said solenoid, a manual switch normally closed and electrically connected to said mercury switch and a buzzer, which is in turn, electrically connected to said transformer, and a timer having motor driven switches operable to

complete a circuit between said transformer and said mercury switch, said mercury switch and said manual switch, said manual switch and said buzzer, and said buzzer to said transformer, whereby a warning is sounded at the expiration of a predetermined time period.

11. A portable safety device including a gas line and a gas burner to which gas under pressure is supplied through the gas line, comprising a circuit including a transformer for supplying current to a mercury switch normally open and operably connected to a pressure responsive device, a solenoid operable to actuate a detent, a valve interposed in said gas line and means normally biasing said valve toward closed position, a switch normally closed interposed between said mercury switch and said solenoid and adapted to be opened upon closing of said valve through actuation of said detent by said solenoid, a manual switch normally closed and electrically connected to said mercury switch and a buzzer, which is in turn, electrically connected to said transformer, and a timer having motor driven switches operable to complete a circuit between said transformer and said mercury switch, said mercury switch and said normally closed switch, said normally closed switch and said solenoid, and said solenoid and said transformer, whereby said detent releases said valve which moves to its closed position to shut off the supply of gas at the expiration of a predetermined time period.

12. A portable safety device including a gas line and a gas burner to which gas under pressure is supplied through the gas line, comprising a circuit including a transformer for supplying current to a mercury switch normally open and operably connected to a pressure responsive device, a solenoid operable to actuate a detent, a valve interposed in said gas line and means normally biasing said valve toward closed position, a switch normally closed interposed between said mercury switch and said solenoid and adapted to be opened upon closing of said valve through actuation of said detent by said solenoid, a manual switch normally closed and electrically connected to said mercury switch and a buzzer, which is in turn, electrically connected to said manual switch and said transformer, and a timer having motor driven switches operable to complete a circuit at the expiration of a predetermined time between said transformer and said mercury switch, said mercury switch and said normally closed switch, said normally closed switch and said solenoid, said solenoid and said transformer, and said mercury switch and said normally closed switch, said normally closed switch and said buzzer, said buzzer and said transformer, whereby the solenoid is energized to actuate said detent to release said valve to move to closed position and the buzzer is sounded at the expiration of a predetermined time period.

13. A portable safety device including a gas line and a gas burner to which gas under pressure is supplied through the gas line, comprising a circuit including a transformer for supplying current to a mercury switch normally open and operably connected to a pressure responsive device, a solenoid operable to actuate a detent, a valve interposed in said gas line and means normally biasing said valve toward closed position, a switch normally closed interposed between said mercury

switch and said solenoid and adapted to be opened upon closing of said valve through actuation of said detent by said solenoid, a manual switch normally closed and electrically connected to said mercury switch and a buzzer which is, in turn, electrically connected to said manual switch and said transformer, a timer having switches operable to complete circuits to said solenoid and said buzzer, and a normally open micro-switch bridging said mercury switch and adapted to be closed by a temperature responsive bi-metallic element upon accidental extinguishment of the flame in said gas burner, whereby the operation of the timer switch is overridden by said micro-switch in times of accidental flame extinguishment regardless of the predetermined time interval as set by said timer, and said gas is shut off in conjunction with the sounding of said buzzer.

14. A safety device in combination with a gas line and a gas burner to which gas under pressure is supplied through said gas line, a valve operably located in the gas line, means for normally biasing the valve towards closed position, a detent arm movable with the valve, a yieldable detent lever adapted to engage the detent arm to hold the valve in open position, a solenoid adapted to operably engage the detent lever, a tiltable mercury switch normally biased towards open position and electrically connected to a source of current supply and to the solenoid, a normally closed bellows communicating with a source of gas under pressure and operable in response to normal gas pressure to engage and hold the mercury switch in open position and also operable to disengage the mercury switch to permit it to tilt to closed position when said gas pressure drops to establish an electric circuit to the solenoid whereby the solenoid actuates the detent lever to liberate and close the valve to cut off the gas supply to the burner, a normally closed switch interposed in the electrical connection between the mercury switch and the solenoid and operably positioned in the path of movement of the detent arm, whereby the arm engages and opens the switch after the valve has moved to closed position, thereby breaking the electric circuit to the solenoid after the gas has been shut off, an electric buzzer electrically connected with said solenoidal, and an electric timer in said last-mentioned electrical connection adapted to simultaneously operate said buzzer and said solenoid at the expiration of a predetermined interval of time.
